RETAINING DEVICE FOR PUMPS, SLIPPERS, AND THE LIKE

Filed June 18, 1928

UNITED STATES PATENT OFFICE

ALBERT L. HOWARD, OF BROCKTON, MASSACHUSETTS, ASSIGNOR TO HAMILTON-WADE COMPANY, OF BROCKTON, MASSACHUSETTS, A CORPORATION

RETAINING DEVICE FOR PUMPS, SLIPPERS, AND THE LIKE

Application filed June 18, 1928. Serial No. 286,345.

This invention relates to a device for retaining low shoes, dancing pumps, slippers, and like foot-wear upon the feet, and particularly upon the feet of ladies.

6 The invention has for its object to provide a retaining device of the character referred to, which is of pleasing external appearance, which is frictionally held in its proper place on the foot, which is adjustable to feet of 10 different sizes, and which is substantially inexpensive.

To this end, the retaining device is provided with a strap member adapted to encircle the foot substantially at the instep portion 15 thereof, and provided on its inner surface with a non-slipping member which serves to hold the strap member from movement on the foot and shoe, and said strap member has secured to it an ornamental member which is 20 located at the instep-engaging portion of the strap and imparts a dressy and pleasing appearance to the retaining device.

The strap member is preferably made of 25 patent or like leather and has its ends connected by an extensible member or piece of elastic goring, which is connected with the ends of the strap member by suitable buckles to permit the strap member to be adjusted to fit feet of different sizes.

30 The non-slipping member is preferably made as a strip of woven rubber fabric.

These and other features of the invention will be pointed out in the claims at the end of this specification.

35 Fig. 1 represents a lady's foot provided with a shoe held thereon by a retaining device embodying this invention;

Fig. 2, a plan view of the retaining device shown in Fig. 1;

40 Fig. 3, a front elevation of the retaining device;

Fig. 4, a section on the line 4—4, Fig. 2, and Fig. 5, a section on the line 5—5, Fig. 2.

45 Referring to the drawing *a* represents the strap member composed of a strip 10 of leather, preferably patent or enamel leather, a layer or strip 12 of cloth or like fabric, which is narrower than the leather strip and is cemented to the inner side thereof to provide the leather strip with side flaps 13, which

are folded over the side edges of the cloth strip and secured thereto by stitches 14 and otherwise.

The cloth strip 12 has cemented or otherwise affixed to it a strip of woven rubber fabric 15 of a width substantially equal to the space between the side flaps 13 and of a thickness greater than that of the side flaps, so that the rubber strip 15 projects beyond the side flaps 13 and forms a friction or holding member which serves to prevent the retaining device from slipping on the foot 17 and on the slipper or shoe 18 thereon.

The strap member *a* has its ends connected together by a piece 20 of elastic goring, which is capable of being stretched to enable the strap member to be readily slipped over the foot and the shoe thereon.

The piece 20 of elastic goring is preferably secured to the ends of the strap member *a* by 70 buckles 23 having intermediate cross bars about which the elastic goring 20 is passed and then secured together at its ends to form a loop.

The ends of the leather strip 10 are engaged with the buckles 23 in a manner well understood and as represented in Fig. 3, to adjustably secure said ends to the extensible member or goring 20.

The strap member *a* is thus made adjustable to feet of different sizes, and by means of the buckles 23, the ends of the leather strip 10 may be adjusted equally, so that when the strap member is provided with an ornamental center piece as herein shown, the latter will be in the same position with relation to the foot 24 in all adjustments of the strap member.

The ornamental center piece may be of any desired design, and in the present instance comprises a piece 30 of patent or like leather having a scalloped edge 31 and a metal ornament 32.

The leather member 30 of the center piece may be secured to the strap member *a* by a metal staple 33 (see Fig. 5), and the metal ornament 32 may be secured to the leather member 30 by stitches 34.

The strap member *a* and the elastic goring 20 form a loop as represented in Fig. 3, which

can be slipped over and under the toe portion of the slipper or shoe 35 and carried back until the looped strap member engages the shank portion of the shoe and the portion of the stocking covering the instep of the foot (see Fig. 1), and when thus positioned the device serves to effectively retain the slipper or shoe on the foot.

The friction member 15 of the retaining device serves to grip the shoe and the foot and prevents the retaining device slipping down toward the toe portion of the shoe.

The ornamental center piece may be made of any desired shape.

15 One embodiment of the invention is herein shown but it is not desired to limit the invention to the particular construction shown.

What is claimed is:

1. A retaining device capable of being 20 slipped over the toe portion of a shoe when on the foot, said retaining device comprising a strap member provided on its inner side with a friction member of greater gripping properties than said strap member, an elastic 25 member, and buckles connecting said elastic member with the ends of said strap member and arranged to permit adjustment of the strap with relation to the buckles, said friction member being arranged with relation to 30 the strap to extend across the instep of the foot and a substantial distance down each side of the foot to frictionally engage with the foot and portion of the shoe.

2. A retaining device capable of being 35 slipped over the toe portion of a shoe when on the foot, said retaining device having a strap member composed of an outer strip of leather, an inner strip of fabric upon which the sides of said outer strip are folded and 40 secured thereto, and a strip of rubber fabric secured to said inner fabric strip between the folded sides of the outer strip to form a non-slipping member for said strap member.

3. A retaining device capable of being 45 slipped over the toe portion of a shoe when on the foot, said retaining device comprising a leather strap member provided on its inner side with a rubber friction member, buckles adjustably secured to each end of the strap, 50 an elastic member secured to the buckles for connecting together the ends of the strap, and an ornamental member on the outside of the strap at or near the center thereof.

In testimony whereof, I have signed my 55 name to this specification.

ALBERT L. HOWARD.
